UNITED STATES PATENT OFFICE

152,035

DESIGN FOR A BALL-BEARING SEPARATOR

John E. Sonnhalter, South Euclid, Ohio, assignor
to Jack & Heintz Precision Industries, Inc.,
Cleveland, Ohio, a corporation of Delaware

Application August 29, 1946, Serial No. 132,950

Term of patent 3½ years

(Cl. D52—1)

To all whom it may concern:

Be it known that I, John E. Sonnhalter, a citizen of the United States, residing at South Euclid, in the county of Cuyahoga and State of Ohio, have invented a new, original, and ornamental Design for Ball-Bearing Separator, of which the following is a specification, reference being had to the accompanying drawing, forming a part thereof, in which:

Figure 1 is a view in perspective of one side of a ball-bearing separator showing my new design;

Figure 2 is a top plan view of the same; and

Figure 3 is a view in perspective of the opposite side of that shown in Figure 1.

I claim:

The ornamental design for a ball-bearing separator, substantially as shown.

JOHN E. SONNHALTER.
